ATTORNEYS.

UNITED STATES PATENT OFFICE.

THOMAS B. BROWN, OF NOROTON, CONNECTICUT.

DESIGN FOR A HANDLED VESSEL.

SPECIFICATION forming part of Design No. 25,857, dated August 4, 1896.

Application filed June 19, 1896. Serial No. 596,216. Term of patent 3½ years.

To all whom it may concern:

Be it known that I, THOMAS B. BROWN, of Noroton, in the county of Fairfield and State of Connecticut, have invented and produced a new and original Design for Handled Vessels, of which the following is a specification, reference being had to the accompanying drawing, forming a part thereof.

The figure is a side elevation of a handled vessel, showing my design.

The design is applicable to all kinds of handled vessels, such as loving-cups, mugs, pitchers, &c.

The leading feature of the design consists

in one or more stag-handles A, each extending 15 from the surface of the vessel B.

The ends of the handle A terminate in raised ornaments C C' on the exterior surface of the vessel to form a space between the handle and the vessel. 20

What I claim is—

The design for a handled vessel, as herein shown and described.

THOMAS B. BROWN.
